CLAIM

The ornamental design for a shoe sole as shown and described.

DESCRIPTION

FIG. 1 is a bottom perspective view of a shoe sole according to our new design;

FIG. 2 is a right side elevation view thereof;

FIG. 3 is a left side elevation view thereof;

FIG. 4 is a front elevation view thereof;

FIG. 5 is a rear elevation view thereof; and,

FIG. 6 is a bottom plan view thereof.

The broken lines in the figures illustrate unclaimed elements that form no part of the claimed design.
